(57) **CLAIM**

The ornamental design for a railway bogie, as shown and described.

DESCRIPTION

FIG. 1 is a top view of the design;

FIG. 2 is a bottom view of the design;

FIG. 3 is a front view of the design;

FIG. 4 is a rear view of the design;

FIG. 5 is a left side view of the design;

FIG. 6 is a right side view of the design;

FIG. 7 is an exploded perspective view of the design; and

FIG. 8 is a perspective view of the design.

FIG. 9 is a top view of the claimed elements of the design shown in isolation from unclaimed elements of the design;

FIG. 10 is a bottom view of the claimed elements of the design shown in isolation;

FIG. 11 is a front view of the claimed elements of the design shown in isolation;

FIG. 12 is a rear view of the claimed elements of the design shown in isolation;

FIG. 13 is a right side view of the claimed elements of the design shown in isolation;

FIG. 14 is a left side view of the claimed elements of the design shown in isolation; and,

FIG. 15 is a perspective view of the claimed elements of the design shown in isolation.

The broken lines shown in FIGS. 1 through 8 illustrate unclaimed subject matter and do not form any part of the claimed design.

1 Claim, 11 Drawing Sheets
